DESIGN FOR A WOVEN TEXTILE FABRIC

Harry Zuckerman, New York, N. Y.

Application June 14, 1937, Serial No. 69,832

Term of patent 3½ years

To all whom it may concern:

Be it known that I, Harry Zuckerman, a citizen of the United States of America, residing in city of New York, county of New York, and State of New York, have invented a new, original, and ornamental Design for a Woven Textile Fabric, of which the following is a specification, reference being had to the accompanying drawing, forming part thereof. The figure on the drawing is a plan view of a woven textile fabric showing my new design.

My design is characterized by a ribbed background having super-imposed nubby yarns arranged in a box-like form.

I claim:

The ornamental design for a woven textile fabric, substantially as shown and described.

HARRY ZUCKERMAN.
